UNITED STATES PATENT OFFICE.

JAMES HAMPTON, OF CHICAGO, ILLINOIS.

FLOOR-SURFACING MACHINE.

1,198,026.

Specification of Letters Patent. Patented Sept. 12, 1916.

Application filed July 14, 1915. Serial No. 39,885.

To all whom it may concern:

Be it known that I, JAMES HAMPTON, a resident of Chicago, in the county of Cook and State of Illinois, have invented certain new and useful Improvements in Floor-Surfacing Machines, of which the following is a full, clear, and exact description.

The invention relates to floor-surfacing machines and more particularly to the type in which a horizontally revolving drum is employed for surfacing the floor.

One object of the invention is to provide an improved floor-surfacing machine in which the mechanism for driving the surfacing drum or shaft thereof is disposed inwardly of the sides of the surfacing drum so that the machine may be worked close to the walls around a floor.

Another object of the invention is to provide a floor-surfacing machine in which the fan for carrying off the dust is disposed so that its shaft extends directly to the drum-shaft and so that simple gearing can be employed for conjointly driving the suction-fan and the drum.

Other objects of the invention will appear from the description of the machine hereinafter given.

The invention consists in the several novel features hereinafter set forth and more particularly defined by claims at the conclusion hereof.

In the drawings: Figure 1 is a side elevation of a machine embodying the invention. Fig. 2 is a plan. Fig. 3 is a detail transverse section of the surfacing-drum, showing one of the devices for securing the surfacing strip on the drum. Fig. 4 is a section taken on line 4—4 of Fig. 3. Fig. 5 is a longitudinal section of the machine, the motor being shown in elevation. Fig. 6 is a section taken on line 6—6 of Fig. 5. Fig. 7 is a section taken on line 7—7 of Fig. 5.

The improved machine comprises a truck with a frame 10 upon which an electric motor 11 is secured. The rear portion of the truck is supported by a pair of wheels 12 which are secured on a spindle 14 journaled in brackets 15 which are secured to a plate 16. Springs 17 are interposed between frame 10 and plate 16 to yieldingly support the frame 10 and motor thereon. Posts 18 extend through one or more of the springs and through slots in the support 10. The carrying-wheels 12, brackets 15, plates 16, and springs 17 serve to yieldingly support

the rear of the machine. In operation, the weight of the front portion of the machine is carried by a two-part surfacing drum 20. The shaft 21 of this drum is mounted in bearings 22 in a bracket 23 which is rigid with the truck-frame 10. A plate 24 is fixed to bracket 23 and is pivoted to plate 16, as at 25, to permit the latter to move relatively to the frame 10 under the influence of springs 17. The drum 20 comprises two sections or members 26, each of which is hollow to provide space for bearings 22 and is provided with a suitable peripheral portion 27 adapted to carry the sandpaper strip 28. Each drum section is rigidly secured to the shaft 21 by a pair of nuts 29. By providing a drum formed of sections, which are separated to accommodate the pendant supporting bracket 23, which is rigid on the truck-frame, the necessity of providing gearing or driving-mechanism at either side of the drum is avoided and as a result, the machine can be operated close to the walls around the floor.

A pair of posts 30 secured to frame 10, are provided with sockets 31 and at their upper ends in which the side bars 32 of a rectangular handle-frame are adjustably held by screws 35. This handle-frame comprises said sides and a front cross-bar 33 and a rear cross-bar 34 rigidly secured together.

A fan-casing 36 is rigid with frame 10 and bracket 23 and may, as shown in the drawings, be integrally formed therewith, if desired, although it will be understood that these parts may be separately formed and rigidly secured together. This fan-casing is horizontally disposed, so that the fan-shaft 37, to which the blades 36^a are secured, will be vertically disposed and is extended through the bracket 23 in which it is journaled. The upper end of shaft 37 is provided with a gear-wheel 38 meshing with a pinion 39 on the shaft 40 of the electric motor 11. The lower end of shaft 37 is provided with a gear 41 meshing with a gear-wheel 42, which is fixed on the drum-shaft 21. This construction exemplifies one in which a common shaft is employed for driving the surfacing drum and the fan. A hood 41^a extends peripherally around the drum to receive the cuttings and guide them to the eye 43 of the fan which communicates with the space between the hood and the drum-sections by means of ducts 44 formed in frame 10. The outlet trunk 36' of the

fan-casing will be connected in any suitable manner to a receiver, as well understood in the art.

Mechanism is provided for propelling the machine by power derived from motor 11. This mechanism comprises a gear 45 meshing with gear 42 and secured to a shaft 46 which has its front end journaled in a bearing 47 in bracket 23 and its rear end journaled in members 48 which are secured to and extend between the wheel-brackets 15. A universal joint 49 is included in shaft 46 to permit the rear portion of the shaft to move relatively to frame 10. A worm wheel 50 is mounted on shaft 46 between members 48 and is adapted to be driven by said shaft through a clutch 51. The worm meshes with a gear 52 on the spindle 14 of the carrying-wheels 12.

20 A roller 52' is provided between the sections of the surfacing-drum and is adapted to lift the front of the machine, including the drum, off the floor, when desired. This roller is secured to a standard 53, which is 25 slidably mounted in lugs 54 on a bracket 55, which is secured to bracket 23. A cushion-spring 56 is interposed between one of the lugs 54' and a collar 57 on the shaft. This roller is adapted to be lowered by a handle 30 58, which is connected to conjointly control clutch 51 and to operate roller 52' so that when the roller is operated to lift the surfacing-drum off the floor, the clutch will be shifted to disconnect the clutch for driving 35 the traction-wheels 12. Handle 58 is secured to a rod 59 which carries a clutch-shifting fork 60 and has its front end connected to a bell-crank 61, which is connected by a link 62 to a collar 63 secured on standard 53. When handle 58 is operated forwardly from the position shown in Fig. 5, it will disconnect clutch 60 to render the driving-mechanism for the wheels 12 inoperative to drive said wheels and will operate 45 the connection for lowering standard 53 sufficiently to lift the drum off the floor and cause the front portion of the machine to be sustained by roller 52'. A tooth 59' is adapted to lock rod 59 in position to hold 50 roller 52' raised.

Each drum-section is provided with a slot 70 adapted to receive the ends of the surfacing strip 28 and a wedge-bar 71, which is adapted to secure the ends of the strip in 55 said slot. The wedge-bar 71 is pivotally connected to a lever 73 which is pivoted as at 74, to the drum. A spring 75 is applied to hold lever 73 in position to cause the wedge-bar to secure the ends of the surfacing stop 28 in slot 70 and an eccentric 76 which is pivoted in the side of the drum-member is adapted to engage the outer end of lever 73 to release the wedge-bar. A handle 77 is secured to the shaft of eccentric 76 and is disposed in a recess 78 in the

side of the drum-member, so that the eccentric can be operated from the outside of the drum.

The invention thus exemplifies an improved floor-surfacing machine, which is simple in construction, in which the drum is driven by means which does not project from either side of the drum; in which there is a direct drive between the fan-shaft and the drum-shaft; and in which provision is made for propelling the machine by power.

70 The invention is not to be understood as restricted to the details set forth, since these may be modified within the scope of the appended claims, without departing from the 75 spirit and scope of the invention.

Having thus described the invention, what I claim as new and desire to secure by Letters Patent, is:

1. In a floor surfacing machine, the combination of a wheeled frame, a surfacing drum connected to the frame and mounted to revolve on a substantially horizontal axis, a horizontally disposed fan on the frame, a motor on the frame, a vertically extending fan shaft driven by said motor and gearing for driving the drum from the fan shaft.

85 2. In a floor surfacing machine, the combination of a wheeled frame, a surfacing drum connected to the frame and comprising two members, a horizontally extending shaft extending through both of the drum members, a motor on the frame, a horizontally disposed fan on the frame, a vertically 90 extending fan shaft driven by the motor and extended downwardly between the drum members and gearing between the vertical fan shaft and the horizontal drum shaft.

95 3. In a floor surfacing machine, the combination of a wheeled frame, a surfacing drum connected to the frame, mounted to rotate on a substantially horizontal axis and comprising a pair of members, a motor on the frame, a horizontally disposed fan on the frame comprising a casing, a vertically 100 extending fan-shaft driven by the motor, a horizontal shaft for both of said drum members, and gearing between the fan shaft and the drum shaft, said fan casing being provided with integral extensions forming a collector hood around the drum members.

105 4. In a floor surfacing machine, the combination of a wheeled frame, a surfacing drum connected to the frame, mounted to rotate on a substantially horizontal axis and comprising a pair of members, a motor on the frame, a horizontally disposed fan on the frame comprising a casing, a vertically 110 extending fan shaft driven by the motor, a horizontal shaft for both of said drum members, and gearing between the fan shaft and the drum shaft, said fan casing being provided with an integral exten- 115

sion between the drum members, having bearings for the drum shaft.

5. In a floor surfacing machine, the combination of a wheeled frame, a surfacing drum mounted to rotate on a substantially horizontal axis and comprising members spaced apart, a motor on the frame, a fan mounted on the frame, driving-mechanism for the drum extending between the drum members, and a collector hood around said members and leading to the fan, the outer ends of the drum and the hood being substantially conterminous so that the drum ends will be free to work close to a wall.
10. In a floor surfacing machine, the combination of a wheeled frame, a surfacing drum comprising members spaced apart, a horizontal shaft for the drum, a motor on the frame, a bracket on the frame extended between said members, and driving mechanism for the drum comprising a vertical shaft mounted in said bracket, said members
15. In a floor surfacing machine, the combination of a frame, carrying-wheels, cushioning means between the frame and the carrying-wheels, a surfacing drum a 20 shaft for the drum, supported in fixed relation to the frame, a motor on the frame, mechanism for driving the drum from the motor, mechanism for driving the carrying-wheels from the drum-driving means, a 25 clutch for controlling the mechanism for driving the carrying-wheels, a roller for lifting the drum off the floor, and means for conjointly controlling the clutch and the roller.
25. In a floor surfacing machine, the combination of a frame, carrying-wheels, cushioning means between the frame and the carrying-wheels, a surfacing drum a 30 shaft for the drum, supported in fixed relation to the frame, a motor on the frame, mechanism for driving the drum from the motor, mechanism for driving the carrying-wheels from the drum-driving means, a 35 clutch for controlling the mechanism for driving the carrying-wheels, a roller for lifting the drum off the floor, and means for conjointly controlling the clutch and the roller.
